UNITED STATES PATENT OFFICE.

ROLAND S. SCHWARZ, SR., OF HUNTINGTON, WEST VIRGINIA.

MOP WRINGER.

Application filed February 7, 1928. Serial No. 252,481.

The present invention relates to a mop wringer and has for its prime object to provide a structure that may be conveniently held in one hand while the mop is pulled 5 through the same with the other hand.

A further very important object of the invention resides in the provision of a mop wringer of this nature which is exceedingly simple in its construction, strong and durable, inexpensive to manufacture, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and 20 claimed.

In the drawing:

Figure 1 is an elevation of the preferred embodiment of the mop wringer,

Figure 2 is another elevation thereof taken 25 at right angles to that shown in Figure 1,

Figure 3 is an elevation of another embodiment of the invention, and

Figure 4 is an elevation of the embodiment 30 shown in Figure 3 taken at right angles to that shown in Figure 3.

Referring to the drawings in detail and particularly Figures 1 and 2 it will be seen that letter L denotes generally substantially L-shaped members each of which comprises arms 5 and 6 disposed at substantial right angles to each other, the arms 5 being curved intermediate their ends as clearly illustrated in Figure 2.

Arms 5 are pivoted together intermediate 40 their ends by suitable pivot means 7. Yokes 8 are pivoted intermediate their ends to the extremities of the arms 6 as at 9 and the extremities of the yokes have journaled therebetween wringer elements in the form of rollers 10. On the extremities of the arms 5 there are fixed handles 11. In this embodiment of the invention it will be seen that the yokes are free to swivel in relation to the members 11. The members L may be 45 pivoted to spread the rollers 10 apart so that the mop may be placed therein and then pivoted to squeeze the mop by the rollers coming together. Obviously the handles 11 may be gripped in one hand and the mop pulled 50 between the rollers with the other hand. It will also be seen that this may be done over

a bucket or the like in a very convenient manner.

Referring now particularly to Figures 3 and 4 it will be seen that the embodiment 60 herein illustrated includes a pair of substantially L-shaped members L' each of which comprises an arm 5' and an arm 6'. Arms 5' are curved intermediate their ends similar to arms 5 and are pivoted together in a 65 similar manner as at 7' and have handles 11' on their extremities. The arms 6' are substantially larger than arm 6 and are provided with laterally extending ears 14 between which are rotatably mounted mop engaging elements in the form of rollers 10'. The operation of this embodiment of the invention is practically identical with that of the first embodiment described except that the rollers are provided with axes rigid in 75 respect to the arms 6'.

It is thought that the construction, operation, utility and advantages of this invention will now be clearly understood by those skilled in this art without a more detailed description thereof.

It will be seen that the structure is simple, may be made strong and durable, at a low cost, and is easy to manipulate and thoroughly efficient and reliable in use.

The present embodiments of the invention have been disclosed in detail merely for the purpose of exemplification since in actual practice they attain the features of advantage enumerated as desirable in the statement 90 of the invention and the above description.

It will be apparent that changes in the details of construction, in the size, and in the combination and arrangement of parts may be resorted to without departing from the 95 spirit or scope of the invention as herein-after claimed or sacrificing any of its advantages.

Having thus described my invention, what I claim as new is:

1. In a mop wringer of the class described, a pair of substantially L-shaped members each including a pair of arms angularly disposed with respect to each other, means pivoting the intermediate portions of two of 105 the arms together, the other two arms extending away from the plane of movement of the first mentioned two arms in the same direction with respect to each other, and mop wringing elements on the second mentioned 110 two arms.

2. In a mop wringer of the class described,

a pair of substantially L-shaped members each including a pair of arms angularly disposed with respect to each other, means pivoting the intermediate portions of two of the 5 arms together, the other two arms extending away from the plane of movement of the first mentioned two arms in the same direction with respect to each other, a pair of mop 10 engaging rollers, and means for journaling the rollers on said second mentioned two arms.

3. In a mop wringer of the class described, a pair of substantially L-shaped members

each including a pair of arms angularly disposed with respect to each other, means pivoting the intermediate portions of two of the 15 arms, together, the other two arms extending away from the plane of movement of the first mentioned two arms in the same direction with respect to each other, a pair of yokes pivoted intermediate their ends to the second 20 mentioned two arms, and rollers journaled in the yokes.

In testimony whereof I affix my signature.
ROLAND S. SCHWARZ, Sr.
